CLAIM

The ornamental design for an exercise equipment, as shown and described.

DESCRIPTION

FIG. 1 is a front-perspective view of an exercise equipment, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 1;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 2; and,

FIG. 18 is a partial enlarged view of FIG. 2.

The broken lines in the figures depict portions of the exercise equipment that form no part of the claimed design. The dash-dot-dash lines are for annotating enlarged views and form no part of the claimed design.

1 Claim, 15 Drawing Sheets
